UNITED STATES PATENT OFFICE

NATHAN WOLFF, OF NEW YORK, N. Y.

UNION SUIT

Application filed March 6, 1929. Serial No. 344,780.

This invention relates to new and useful improvements in undergarments for masculine wear and more particularly to a union suit, the primary object of the invention being to provide a garment of the character mentioned which is designed to produce and provide the utmost comfort and convenience in the wear thereof at all times.

A further object of the invention resides in constructing a union suit so that the posterior or rear section thereof will be free from buttons and other securing means but which is also designed to automatically position itself properly on the body of the wearer and permit movements of the body in all directions without causing undue strains on any portion of the garment.

Still another object of the invention resides in forming the rear half of the waistband, forming the upper edge of the posterior section, with a hem or casing in which is secured an elastic band engaged with the sides of the garment, so that the posterior section after having been drawn down against the tension of the elastic band will be automatically returned to its normal and proper position.

A further object resides in providing a flap depending from the back portion of the garment which is secured to the sides or leg portions adapted to be covered by the posterior section of the garment when said latter section is returned to its normal position and which will prevent the rear or back section of the garment from being drawn upwardly or "buckled" upon the return of the posterior section to its normal position.

With these and numerous other objects in view, my invention consists in the novel features of construction, combination and arrangement of parts as will be hereinafter referred to and more particularly pointed out in the specification and claim.

In the accompanying drawing, forming a part of this application,

Figure 1 is a front elevation of the garment;

Figure 2 is a rear elevation thereof, with parts broken away;

Figure 3 is a fragmentary perspective view

showing in detail the elastic band in its casing; and

Figure 4 is a fragmentary detail elevation showing clearly the stitching of the elastic band and the casing therefor, with respect to the garment.

Union suits for masculine wear appear to be the most popular at the present time and as the greater proportion of such garments now being manufactured have some form of fastening means such as buttons and the like, in the rear or side, which fastening means is usually damaged in laundrying, considerable inconvenience and discomfort is had in the wearing and use thereof. My invention contemplates the provision of a garment of the type mentioned which eliminates the use of such fastening means in the rear or sides and which is provided with an elastic to return the posterior section automatically to its normal position around the waist of the wearer and which will at the same time permit of the various movements of the body without undue strain on any portion of the garment.

To this end, I provide a garment composed of frontal sections 1 and 2 secured together along the front by the buttons or other similar or analogous fastening means 3. These frontal sections, of course, are secured along the side edges thereof to a back section 4. The lower portions of the frontal sections 1 and 2 are formed into front portions of leg sections of the garment and there is also provided a posterior section 5 which is comprised of two sections secured together centrally along the line designated by the numeral 6, the side or marginal edges of the posterior section being secured to the frontal sections 1 and 2 along the leg portions up to the waist portion of the garment. The rear or posterior section 5 has considerable fullness in the seat thereof, as is usually provided in garments of this character.

As stated above, one of the principal features of my invention is to provide a garment eliminating the use of buttons or fastening devices from the posterior section and in carrying out this object, the upper edge of the posterior section is provided with a hem or casing 7 in which is introduced an elastic

band 8 of less length than the casing, the hem or casing being gathered over said band. The ends of this elastic band 8 are stitched as shown at 9 to the side seams or stitching between the frontal and posterior sections 5 and in addition to this stitching, the band 8 is also stitched to the hem or casing 7 as shown at 10 inward of said stitching 9. Thus, should it occur through use that the 10 elastic band is disengaged from one member it will be secured to another and will not become entirely disengaged and ineffective.

The elastic band extends the full width, from side to side, of the posterior section, 15 although normally of less length than one half of the waist band of the garment, and in this manner the posterior or rear section is normally held in proper position about the body of the wearer. This posterior section 20 may be drawn down under the knees of the wearer when necessary, but under the action of the elastic band, will automatically return to its proper and normal position and fit snugly around the waist of the wearer, without the necessity of buttons or other fastenings means. In order that the automatic return of this posterior section to its normal 25 position will not cause any buckling up of the lower portion of the back section 4 and in order that it will not be necessary for the 30 wearer to shove in the rear of the back section, I extend the back section 4 downwardly a sufficient distance to form a depending flap 11 which extends below the band approximately 35 six or seven inches. This flap is permanently stitched along its side edges to the side seams as shown at 12 so that in the return of the posterior section to its normal position, under action of the elastic band 8, the 40 lower end of the posterior section will not be carried along with it and there will be no buckling up of the sections of the garment. The lower edge of this flap 11 is concave as shown at 13 for obvious purposes.

45 From the foregoing description of the construction of my improved garment, the manner of forming the same and its use on the body will be readily understood, and it will be seen that I have provided a simple, inexpensive and efficient means for carrying out 50 the objects of the invention. It will be further seen that with my improved garment the use of an elastic webbing in the back section of the garment to permit ease in 55 bending will be eliminated, since this is taken care of by the elastic band in the upper edge of the posterior section as heretofore described.

Various changes in form, proportion and 60 in the minor details of construction may be resorted to without departing from the spirit or sacrificing any of the principles of the invention.

Having thus described my invention, what

65 I claim is:

A union suit comprising front, back and posterior sections, the back section terminating above the crotch portion of the front section and stitched along side edges of the front section for the full depth of the back section, the posterior section overlapping the lower portion of the back section and stitched along its side edges to side edges of the front section and the overlapped portion of the back section, a marginal casing being formed across the upper end of the posterior section for the full width thereof, and an elastic band within said casing stretched and having its ends secured at the ends of the casing, said casing being secured at its ends 70 with seams connecting the front and back sections and free from the back section for the remainder of its length.

In testimony whereof I affix my signature.
NATHAN WOLFF.
